UNITED STATES PATENT OFFICE.

FREDRECH AHRENS, OF NEW YORK, N. Y.

PROJECTILE.

SPECIFICATION forming part of Letters Patent No. 620,400, dated February 28, 1899.

Application filed August 18, 1898. Serial No. 688,926. (No model.)

To all whom it may concern:

Be it known that I, FREDRECH AHRENS, a citizen of the United States, residing at New York, (Tarrytown,) in the county of West-
5 chester and State of New York, have invented a new and useful Projectile for Use in Naval Guns and Artillery, of which the following is a specification.

My invention relates to improvements in ar-
10 mor-piercing projectiles by which a projectile smaller than the caliber of the gun is fired; and the object of my improvements is to pro-
15 vide a projectile which will have a great pene-
trating power and capable of being thrown
from the muzzle of a gun to an exceedingly
long range, and when a long projectile is used
20 possesses the capability of being fired at a
point below the water's edge without deflec-
tion. I attain these objects by the construc-
tion illustrated in the accompanying draw-
ings, in which—

Figure 1 is a side view of the entire proj-
25 ectile; Fig. 2, a view of the rear or back
plate; Fig. 3, a view in perspective of a sec-
tion of the steel projectile, showing the rear
end; and Figs. 4 and 5 are perspective views
20 showing the wooden jacket when open and
separated.

Similar letters refer to similar parts through-
30 out the several views.

The jacket J, Figs. 4 and 5, is composed of
35 wood in two pieces, each part having the shape
of a semicylinder, the two parts being held
together by two wooden pins p p, the front
ends being slightly bottle-necked on the out-
side to insure easy entry into the breech of a
40 gun. This cylinder is made to fit the breech
and may be made any required size. The
steel projectile fits inside the cylinder when
the two parts are fastened together. The

front end of the jacket J is hollowed out in
a cup or funnel shape h, Figs. 4 and 5, and
the rear end is mortised, r r and l l. The
rear plate P is made of steel or iron and has
projecting ribs r along the inner surface, form-
45 ing a hollow square to receive the squared
end e of the steel projectile, Fig. 3. The plate
is also furnished with lugs l, which, together
with the ribs r, fit into the mortises r r and l l,
Figs. 4 and 5. The plate P is also fastened
50 to the jacket J by four screws s.

When the projectile fitted together as in
Fig. 1 is propelled from the mouth of a gun,
the force of the explosion and the air-pres-
55 sure in the hollow end of the jacket created
by its great velocity and the rotary motion
of the projectile will cause the jacket J to
separate and the two pieces and the plate P
to fall to the ground, while the steel projec-
60 tile is propelled with great force at the ob-
ject aimed at. The proper accuracy is ob-
tained by the jacket J and the plate P re-
ceiving a rotary motion by passing through
the rifling of the gun-barrel. The projectile
65 B may or may not have an explosive head.

What I claim as my invention, and desire
to secure by Letters Patent, is—

The combination with a projectile having a
square rear end, of a wooden jacket, cylinder-
shaped in two parts, hollowed out in the front,
70 cut with mortises at the rear end, a steel plate
having a square recess in which rests the
square end of the projectile and with ribs
and lugs to enter the mortises in the rear of
the jacket, all substantially as set forth.

FREDRECH AHRENS.
